CLAIM

The ornamental design for a lighting fixture, as shown and described.

DESCRIPTION

FIG. 1 is a front perspective view of a new lighting fixture; FIG. 2 is a back perspective view thereof;

FIG. 3 is a front elevation view thereof;

FIG. 4 is a back elevation view thereof;

FIG. 5 is a left elevational view thereof;

FIG. 6 is a right elevation view thereof;

FIG. 7 is a top plan view thereof; and,

FIG. 8 is a bottom plan view thereof.

The broken line disclosure in the views represents portions of the fixture that form no part of the claimed design. The broken-line extending out beyond the perimeter of the back surface of the fixture in FIGS. 5-8 is intended to demonstrate environment only and forms no part of the claimed design.
